Primary Examiner — Paula Allen Greene*(74) Attorney, Agent, or Firm* — Cantor Colburn LLP**CLAIM**

We claim the ornamental design for a wireless earphone, as shown and described.

DESCRIPTION

FIG. 1 is a left-side perspective view of a wireless earphone, showing our new design;

FIG. 2 is a front view thereof;

FIG. 3 is a rear view thereof;

FIG. 4 is a left-side view thereof;

FIG. 5 is a right-side view thereof;

FIG. 6 is a top view thereof; and,

FIG. 7 is a bottom view thereof.

The broken lines in the figures depict portions of the wireless earphone that form no part of the claimed design.
